UNITED STATES PATENT OFFICE.

GEORGE W. BALL, OF BOISE, IDAHO.

DESIGN FOR A BADGE, CHARM, OR SIMILAR ARTICLE.

43,175.

Specification for Design.

Patented Oct. 22, 1912.

Application filed June 24, 1912. Serial No. 705,666. Term of patent 7 years.

To all whom it may concern:

Be it known that I, GEORGE W. BALL, a citizen of the United States, residing at Boise, in the county of Ada and State of Idaho, have invented a new, original, and ornamental Design for a Badge, Charm, or Similar Article Designed for the Order of Elks, of which the following is a specification, reference being had to the accompanying drawing, forming a part thereof.

The figure is a plan view of a badge showing my new design.

I claim:

The ornamental design for a badge, charm or similar article designed for the Order of Elks.

GEORGE W. BALL.

Witnesses:

RICHARD M. D. CHILDS,
GUSTAVE R. MUELLER.
